(57) **CLAIM**

The ornamental design for a sign for a shelf, substantially as shown and described.

DESCRIPTION

FIG. 1 is a front perspective view of the sign for a shelf according to a first embodiment;

FIG. 2 is a front elevational view of the sign for a shelf of FIG. 1;

FIG. 3 is a rear elevational view of the sign for a shelf of FIG. 1;

FIG. 4 is a left elevational view of the sign for a shelf of FIG. 1;

FIG. 5 is a right elevational view of the sign for a shelf of FIG. 1;

FIG. 6 is a top view of the sign for a shelf of FIG. 1;

FIG. 7 is a bottom view of the sign for a shelf of FIG. 1;

FIG. 8 is a front perspective view of the sign for a shelf according to a second embodiment;

FIG. 9 is a front elevational view of the sign for a shelf of FIG. 8;

FIG. 10 is a rear elevational view of the sign for a shelf of FIG. 8;

FIG. 11 is a left elevational view of the sign for a shelf of FIG. 8;

FIG. 12 is a right elevational view of the sign for a shelf of FIG. 8;

FIG. 13 is a top view of the sign for a shelf of FIG. 8;

FIG. 14 is a bottom view of the sign for a shelf of FIG. 8;

FIG. 15 is a front perspective view of the sign for a shelf according to a third embodiment; and,

FIG. 16 is a front perspective view of the sign for a shelf according to a fourth embodiment.
